UNITED STATES PATENT OFFICE.

WILLIAM E. BADGER, OF QUINCY, MASSACHUSETTS.

WRENCH.

SPECIFICATION forming part of Letters Patent No. 502,870, dated August 8, 1893.

Application filed August 22, 1892. Serial No. 443,753. (No model.)

To all whom it may concern:

Be it known that I, WILLIAM E. BADGER, of Quincy, in the county of Norfolk and State of Massachusetts, have invented certain new and

5 useful Improvements in Wrenches, of which the following is a specification.

This invention has relation to wrenches generally, and has for its object the provision of improvements which will cause the wrench to 10 take a firmer hold upon the object to which it may be applied, and "let go" more readily and with greater certainty than is the case with wrenches now commonly used. Other quite important purposes are also had in view 15 in the making of my improvements as will fully appear from the description and claims appearing hereinafter.

My invention consists in the wrench comprising the features of construction herein- 20 after described and claimed.

Reference is to be had to the annexed drawings, and the letters marked thereon, forming a part of this specification, the same letters designating the same parts or features, as the 25 case may be, in both views.

Of the drawings—Figure 1 is a side elevation of my improved wrench, complete. Fig. 2 is a sectional side view, part of the handle being represented as broken off.

30 It will, perhaps, be sufficient to describe my improvements as applied to a pipe wrench, though it will appear obvious that they may be employed in connection with monkey wrenches as well.

35 In the drawings *a* designates the handle of the wrench, the forward end of which is provided with ears *b* in which is pivoted the shank *c* of the longitudinally movable jaw *d*.

e designates a jaw for co-operating with the 40 jaw *d*, which jaw *e* is pivoted in a recess *f* formed in the end of the handle *a*, and *g* is a spring interposed between the jaws *d* and *e*, which spring operates with a tendency to separate the jaws. Any form and arrangement 45 of spring may be used. As herein shown a helical spring is employed, one end of which is seated in a recess formed in the upper surface of the jaw *e* with the other end bearing against the lower surface of the shank of the

50 jaw *d*. The shank *c* of the jaw *d* is, for con-

venience, slotted, as at *h*, and the rearward end of the said shank is constructed as a nut *i*, through which the adjusting screw *j* is tapped, as shown.

k designates a socketed nut arranged in the 55 slot *h* of the shank *c* and provided with a hole for the reception of the pivot pin *l* which also passes through the ears *b* of the handle. The inner end of the adjusting screw *j* is seated in the socket of the nut *k* and is provided with 60 a groove *m* for the reception of a pin *n* which passes also through one side of the nut *k* at its socketed point. With this construction it will be seen that the shank *c* will be arranged so that it may rock on the pivot pin 65 *l*, and by turning the screw *j* the jaw *d* may be adjusted to any desired position longitudinally of the handle and with respect to its nearness to or distance from the jaw *e*. By pivoting both jaws, as described, a construction 70 is provided which permits both jaws to readily adjust themselves to the pipe or other thing acted upon so as to take the most secure hold, and the spring *g* acting upon both pivoted jaws opens or separates the same so 75 as to cause the same to "let go" upon the instant there is a let up of exertion on the handle.

The nut *i* may be made as long as desired so as to give the thread of the screw *j* as long a bearing in the said nut as may be necessary 80 to prevent a stripping of the thread; and said thread may be made square and as coarse as may be thought best.

Having described the nature of my invention and explained a way of constructing and 85 using the same, I declare that what I claim is—

1. A wrench, comprising in its construction, a handle, a jaw pivoted in the end of the handle, a rocking jaw movable longitudinally of 90 the handle, a screw independent of the handle and arranged parallel with the same for adjusting the rocking jaw only, and a spring interposed between the two jaws beyond the pivotal point of the rocking jaw and pressing 95 with equal force against the two jaws to separate them, as set forth.

2. A wrench comprising in its construction a handle and jaw pivotally connected therewith, a longitudinally movable jaw and its 100

shank pivoted on the handle, said shank being provided with a slot, a socketed nut through which the pivot pin of the shank passes, and an adjusting screw tapped through a nut forming part of said shank, and connected with the socketed nut, as described.

5 In testimony whereof I have signed my

name to this specification, in the presence of two subscribing witnesses, this 5th day of August, A. D. 1892.

WILLIAM E. BADGER.

Witnesses:

ARTHUR W. CROSSLEY,

WALTER S. MCLEOD.
